Primary Examiner — Susan Bennett Hattan*Assistant Examiner* — Leanne Was(74) *Attorney, Agent, or Firm* — Hayes Soloway P.C.(57) **CLAIM**

The ornamental design for a bottle, as shown and described.

DESCRIPTION

FIG. 1 is a front view of a bottle showing my design, the back view being a mirror image thereof;

FIG. 2 is a side view of the bottle, the opposite side being a mirror image thereof;

FIG. 3 is a top view of the bottle;

FIG. 4 is a top perspective view of the bottle;

FIG. 5 is a bottom view of the bottle; and,

FIG. 6 is a side perspective view of the bottle.

The broken lines depict portions of the bottle that form no part of the claimed design.

1 Claim, 6 Drawing Sheets(56)
